GEARING.

1,072,538.

Specification of Letters Patent.

Patented Sept. 9, 1913.

Application filed May 29, 1911. Serial No. 630,252.

To all whom it may concern:

Be it known that I, SERN P. WATT, a citizen of the United States, residing at Seattle, in the county of King and State of Washington, have invented certain new and useful Improvements in Gearing, of which the following is a specification.

This invention relates to gearing, and particularly to that class of devices which are utilized for transmitting the motion of a power shaft to the drum of a hoisting machine to drive the drum in the same or in reverse rotary directions, the winding drums of hoisting engines being a familiar example of power thus transmitted.

The object of my invention is the improvement of this class of power transmitting devices so as to render the same more powerful and efficient in use.

The invention consists in the novel construction and combination of parts, as will be hereinafter described and claimed.

In the accompanying drawings, Figure 1 is a side elevation of a hoisting engine of ordinary construction with the driving gear shown diagrammatically. Fig. 2 is a plan view of a portion of a hoisting engine of the type shown in the preceding view, illustrating, in horizontal section, my invention applied thereto.

The reference numerals 5 and 5' indicate side members of the machine frame which are provided with journal boxes, such as 6, 7 and 8, to respectively accommodate the power shaft 6', the drum shaft 7' and an intermediate shaft 8'. Fixedly secured to said drum-shaft, as by a key 9, is a spur gear 10 which is driven directly from a toothed pinion 11 provided on the power shaft 6'. As illustrated, there are two winding drums 12 and 13 which are loosely mounted upon the drum-shaft at opposite sides of said spur gear. These drums are each formed at their ends adjacent to the spur gear with annular grooves 14 and 14' to serve as clutch elements complementary to annular projections 15 and 15' provided upon the sides of the spur gear. Interposed between said spur gear and the drums are helical springs 16 and 16' tending to press the respective drums from the spur gear to disengage the clutches thereof.

The engagement of the clutch elements for either of the drums may be accomplished by any means suitable for attaining an end-

wise movement thereto and for overcoming the power of the affected spring.

As illustrated, there is provided for each drum a screw bolt 17 or 17' extending through a threaded hole in a yoke 18 or 18', 60 rigid with a side member of the machine frame and into a socket provided in the adjacent end of the drum shaft 7' to bear against a bar 19 or 19' extending diametrically of the shaft through a longitudinal 65 slot of the latter.

20 and 20' represent collars intermediate bars 19 and 19' and the hubs of the adjacent drums to afford a relatively large bearing surface against the latter. The drum 12 is 70 formed with, or has fixedly secured thereto a toothed gear 21 which is in continuous mesh with a pinion 22 which is secured for rotation to the intermediate shaft 8'. A second gear 23 is loosely mounted on 75 the intermediate shaft and is adapted to be coupled with the pinion 22 through the instrumentality of clutch elements such as the annular projection 24 and the groove 25 provided therefor on the respective parts. 80 The engagement of these clutch elements may be attained through the agency of devices similar to those described for the aforesaid drum-clutches; namely, a screw bolt 17'', extending through a yoke 18'' and bearing against a bar 19'' which, in turn, presses against a collar 20'' which is juxtaposed with the hub of the gear 23. The gear 23 is driven by a pinion 26 upon the power shaft 6'. 27 is a spring acting to separate 85 the gear 23 from the pinion 22 when the screw bolt 17'' is retracted.

As illustrated, the drum 13 is arranged to be driven in but one direction and is operated through the agency of the spur 95 gear 10 when the latter is coupled thereto by the engagement of the associated clutch elements 14' and 15' when brought together through the office of the screw bolt 17', as will be understood. When the clutch elements are separated by the spring 16' after the bolt 17' is retracted, the drum 13 will become idle. The other drum 12 derives a similar motion from the referred to spur gear when the respective clutch elements 100 14-15 are actuated through the medium of the screw bolt 17; and also becomes inoperative with respect to the spur gear when this drum is uncoupled therefrom, as represented in Fig. 2.

The reverse motion of the drum 12 is attained by actuating the screw bolt 17" to couple the gears 22 and 23 through the medium of the clutch elements 25 and 24 provided thereon. The ensuing action would then be that the gear 23 which is continuously driven from the pinion 26 when the power shaft is operated would transmit motion to the gear 22 when the drum connected gear 21 is rotated to correspondingly drive the drum.

What I claim is—

In a hoisting machine, the combination of a power shaft, a toothed pinion thereon intermediate the ends of the shaft, a second pinion on said shaft adjacent one end thereof, a driven shaft, a spur gear fixedly mounted on said driven shaft and in mesh with

the first-named pinion, a clutch member carried by said spur gear, an element rotatably-mounted on the driven shaft and adapted to be engaged with said clutch member, an intermediate shaft, two gears upon said intermediate shaft near one end which mesh respectively with the second-named pinion and the rotating element, and means whereby the gears of the intermediate shaft may be coupled for driving the rotating element in a direction contrary to that afforded by the first-named pinion and the spur gear which is in mesh therewith.

SERN P. WATT.
